UNITED STATES PATENT OFFICE

FRED C. ANDERSEN, OF BAYPORT, MINNESOTA

WINDOW FRAME

Application filed February 3, 1930. Serial No. 425,624.

In the manufacture of window frames, a standard width of jamb is usually provided, but often there is a call for a jamb of less than standard width. It then becomes necessary to either cut down the standard width jamb or provide a jamb of less width than standard. The standard width jamb in one piece has, with the increasing cost of lumber, added to the expense of the frame, and if the manufacturer attempts to carry jambs of different width in stock, he will not only find it difficult to keep supplied with the desired dimensions, but will add quite materially to the expense of manufacturing and selling the frames. To obviate this difficulty, I find an economical way of constructing a frame is to build up a narrow jamb of less than standard width, to one of the desired standard width, by the use of an inner liner strip at the inner edge of the jamb, and when there is a call for a frame with a jamb of less than standard width it may be easily obtained by merely removing the liner strip. This use of the liner strip on the inner edge of each jamb, not only enables me to provide a jamb of any width desired, but I am also able to economize in the use of lumber, for evidently a comparatively narrow jamb with a liner strip secured thereto, would be less expensive than a jamb made in a single piece, the full width of the narrow jamb and the liner strip. Furthermore, the use of the liner strip allows the convenient change in the width of the jamb without the necessity of cutting the lumber, and the change can be made with comparatively little expense.

A further advantage in the use of the inside liner, lies in the fact that it may be thicker than the abutting edge of the jamb, a feature of importance frequently in applying the inside trim, without the necessity of using a piece of lumber of greater thickness than is required for the jamb itself.

The object of my present invention is to utilize this liner strip in making a windproof joint between the jamb and the sheathing that is interposed in building construction between the jamb and the lath and plaster.

A further object is to utilize this inner liner strip in making this air-proof joint so that it

becomes unnecessary to groove and thereby weaken the inner portion of the jamb itself.

A further object is to provide an airproof construction on the inner side of the frame co-operating with the narrow blind stop and the sheathing associated therewith on the outer side of the frame to complete the windproof walls around the window weight box.

The invention consists generally of various constructions and combinations, all as herein-after described, and particularly pointed out in the claim.

In the accompanying drawing forming a part of this specification

Figure 1 is a perspective view of a portion of the window frame embodying my invention looking toward the inner side of the frame; and

Figure 2 is a sectional view on the line 2—2 of Figure 1.

In the drawing, 2 represents a window sill, and 3 the jambs having the usual central parting bead 4 and provided at the outer edge with narrow blind stops 5 and the sheathing strips 6 having tongue and groove joints 7 with the blind stops to provide a structure adapted for either narrow or wide blind stop construction, all as described and claimed in my U. S. Patent, No. 1,595,958, dated August 10, 1926. A studding 8 is arranged parallel with the jambs 3 and separated therefrom to form the usual weight box 9. At the inner edge of each jamb I provide an inner liner 10 made of a strip of fibrous material of suitable width and secured by suitable means to the edge of the jamb and forming an inward continuation thereof. In making the frame, I prefer to provide a comparatively narrow jamb and then bring its width up to the standard by the use of the inner liner strip and of course the width of this strip may be increased or decreased as desired so that any width of jamb may be provided. Furthermore, if for any reason it is desired to use a jamb of less than the standard width, the liner strips can be easily and quickly separated from the jambs and entirely removed from the window frame.

I have also found in the manufacture of window frames that unless comparatively

thick stock is used for the jambs, it is not desirable to groove the faces thereof for the purpose of making wind or dustproof joints, but by providing the inner liner strip, I may groove the outer edge thereof and still use comparatively thin material for the jamb itself. I thus avoid the more expensive, thicker material for the jamb and at the same time provide the desired wind and dustproof joint between the jamb and the inside trim or finish.

Furthermore, in the manufacture of window frames, it is often necessary to provide a considerable thickness of material at the inner edge of the jamb and the use of the liner strip enables me to provide such thickness without the necessity of making the whole jamb of thicker material. I am thus able with the use of the liner strip, to not only economize in the width of the lumber used for the jamb, but also in the thickness of such lumber.

When the liner strip is secured to the edge of the jamb, it not only provides for the desired width corresponding to the depth of the window frame, but the edge of the strip may be grooved as indicated at 11 and then a sheathing strip 12 having a tongue 13 may be interposed between the liner and the lath and plaster 14. In this way a close air-tight joint is made between the jamb and the sheathing strip without the necessity of providing a jamb the full depth of the window frame or of sufficient thickness so that a groove may safely be made in the adjacent face. These liner strips may be made of material having little value other than for this purpose and of course the width of the strips may be varied according to the desired dimensions of the sheathing interposed between the liner and the lath and plaster. In distinction from the narrow blind stop, the exposed edge of the liner strip will be flush or substantially so with the exposed face of the jamb as shown plainly in Figure 2, while the blind stop projects beyond the face of the jamb.

It will be understood that these liner strips may be made of different thickness according to the additional width desired for the jamb and having been firmly secured to the edge of the jamb, become in effect, an integral part of it, practically as solid and substantial as though the jamb and liner strip were formed in one piece.

In various ways the details of construction herein shown and described may be modified and still be within the scope of my invention.

I claim as my invention:

In a window frame, a narrow blind stop adapted to be inserted between the jamb and the outside casing and projecting inwardly beyond the face of the jamb, and a board wider than said stop having an edge to edge closed joint therewith and forming an out-

ward continuation of said stop, an inner liner strip secured to the inner edge of the jamb and having one exposed edge face flush substantially with the normally exposed face of the jamb and forming a continuation thereof and said strip extending laterally beyond the normally concealed face of the jamb and a board having an edge to edge closed joint with the other edge face of said liner strip and forming a lateral continuation thereof.

In witness whereof, I have hereunto set my hand this 30th day of January 1930.

FRED C. ANDERSEN.
